UNITED STATES PATENT OFFICE.

HUBERT J. BOEKEN, OF DUREN, GERMANY.

RAMIE-DECORTICATOR.

No. 877,983.

Specification of Letters Patent.

Patented Feb. 4, 1908.

Application filed July 24, 1906. Serial No. 327,511.

To all whom it may concern:

Be it known that I, HUBERT J. BOEKEN, civil engineer, a subject of the King of Prussia, residing at Dueren, Rhineland, No. 6 5 Hohenzollernstrasse, in the Kingdom of Prussia, Empire of Germany, have invented certain new and useful Improvements in Ramie-Decortic平ators; and I do hereby declare the following to be a full, clear, and 10 exact description of the invention, such as will enable others skilled in the art to which it appertains to make and use the same.

My present invention relates to decortic平ators and more particularly to a decortic平ator 15 designed for detaching the rind from the stalks of the different varieties of the ramie plant to which end the stalks are fed lengthwise by feed-rollers through a guide-slot formed by rigid lips and upon leaving said 20 slot are broken or nicked across the lower longitudinal edges of said rigid lips by teeth oscillating in front of said two lips in a manner to detach the rind from the woody substance of said stalks and at the same time 25 eliminate the broken or nicked woody and pithy parts thereof.

In the accompanying drawings:—Figure 1 is a side view of the decortic平ator, partly in section. Fig. 2 is a sectional view taken on 30 line A—B of Fig. 1. Fig. 3 is an elevation of the adjustable connection between one of the motion-links and one of the rocker-arms employed for oscillating the knifelike decortic平ating teeth. Fig. 4 is a partial sectional view taken on line C—D of Fig. 3.

The frame 1 of the decortic平ator consists of the side-parts 2 and 3 rigidly connected with each other by means of the stay-rods 4. In the rear end of the frame 1 is journaled the 40 driving-shaft 5 provided with a fly-wheel 6, a spur-wheel 7 and a chain-wheel 8, of which the spur-wheel 7 serves to impart motion to the oscillating teeth 9 and 10, and the chain-wheel 8 to drive the means for feeding the 45 ramie-stalks 11 towards said oscillating teeth.

On rotating the driving-shaft 5 by means of the crank-handle 12 of the fly-wheel 6, the spur-wheel 7 will transmit its motion to the spur-wheel 13 of the intermediate shaft 14 50 and to the spur-wheel 15 likewise seated on the intermediate shaft 14. The spur-wheel 15 meshes with the pinion 16 of the second intermediate shaft 17 which carries at its free ends eccentrics 18 surrounded by the 55 strap-ends of the motion-links 19. The free ends of these links are provided with pins 20,

which may be adjusted in the slots 21 of the rocker-arms 22 seated on the shaft 23 to regulate the throw of the teeth 9 and 10. This shaft 23 is journaled in the brackets 24 60 arranged on the front-side of the frame 1 and carries two arms 25 provided with concentric faces to which the blunt-edged knife-like teeth 9 and 10 are secured. It is evident that by means of this arrangement the 65 teeth 9 and 10 are compelled to oscillate when the driving-shaft 5 is rotated, and that the degree of this oscillating motion can be altered at will by changing the position of the pins 20 in the slots 21 of the rocker- 70 arms 22.

On top of the frame 1 a table or platform 26 is arranged and in front of it the feed-rollers 27, 28 and 29. Of these feed-rollers the roller 27 is journaled in the side-parts 2 and 3 75 of the frame 1 and its fixed shaft 30 carries a spur-wheel 31 and a chain-wheel 32, of which the latter receives its motion from the chain-wheel 8 by means of the chain 33. Vertically over the feed-roller 27 the vertically 80 movable feed-roller 28 is arranged. The ends of the shaft 34 of this feed-roller are journaled in bearing-boxes 35 which slide in guide-slots 36 of the side-parts 2 and 3. These 85 slots are closed at their upper ends by caps 37 of which each is provided with a pin 38 to retain a pressure-spring 39, by means of which springs the feed-roller 28 is continually pressed downward, whereas its rotation is caused by the friction of the stalks 11 advanced by the feed-rollers 27 and 29. The feed-roller 29 is arranged in front of the feed-rollers 27 and 28, as shown in Fig. 1, and receives its motion from the spur-wheel 31 of the shaft 30 of the feed-roller 27, which spur-wheel 95 meshes with the spur-wheel 40 secured to the shaft 41 of the feed-roller 29. In advance of the feed-rollers 27 and 29 two rigid lips 42 and 43 are firmly secured to the side-parts of the frame 1 and arranged, in a 100 manner to form a guide-slot 44 for the guidance of the stalks 11.

If now the ramie-stalks are placed on the table 26 and the driving-shaft 5 set in rotation, the stalks 11 will be fed by means of 105 the feed-rollers 27, 28 and 29 through the guide-slot 44 and upon leaving the latter will pass between the teeth 9 and 10 which through their oscillating action will alternately break or nick said stalks across the 110 lower longitudinal edges of the lips 42 and 43 in such a manner, that the rind is completely

separated from the woody parts of the stalks but not injured. The woody and pithy parts of said stalks are hereby broken up into small pieces, which through the uninterrupted oscillating action of the teeth 9 and 10 are separated from each other and shaken off the detached rind. The rind of the stalks thus detached from the woody parts of the ramie stalks may then be removed by hand or automatically.

I claim:—

1. In a ramie-decorticator the combination of a stalk-feeding device, rigid lips forming with their opposing faces a guide-slot and 15 with their outer side-faces a concave surface, knifelike teeth facing each other and oscillating adjacent said concave surface, and means for regulating the degree of oscillation of said teeth, substantially as shown and 20 described.

2. In a ramie-decorticator the combination of a stalk-feeding-device, rigid lips forming with their opposing faces a guide-slot adjacent said feeding device and with their outer side-faces a uniformly curved concave 25 surface, blunt-edged knifelike teeth facing each other and oscillating adjacent said concave surface, adjustable means for regulating the throw of said oscillating teeth, and means for operating said feeding device and 30 said oscillating teeth, substantially as shown and described.

In testimony whereof I have signed my name to this specification in the presence of two subscribing witnesses.

HUBERT J. BOEKEN.
